UNITED STATES PATENT OFFICE.

JOHN NEUROTH, OF SYRACUSE, NEW YORK, ASSIGNOR TO HARRY B. KNECHT, OF SYRACUSE, NEW YORK.

WARP-TENSIONING DEVICE FOR LOOMS.

Application filed February 3, 1923. Serial No. 616,677.

To all whom it may concern:

Be it known that I, JOHN NEUROTH, a citizen of the United States of America, of Syracuse, in the county of Onondaga, in the State of New York, have invented new and useful Improvements in Warp-Tensioning Devices for Looms, of which the following, taken in connection with the accompanying drawings, is a full, clear, and exact description.

This invention relates to a warp tensioning device as used more particularly in silk weaving in which the requirements for uniform tension and for varying the tension according to the nature of the silk are more exacting than in many other lines of weaving and the main object of my present invention is to provide simple and efficient means for maintaining this uniform tension and for easily and quickly varying it according to the nature of the work or on the same work as the leverage on the beam varies during the unwinding of the warp therefrom.

In other words, I have sought to make use of a series of coaxial rotary carriers or drums having internal buckets carrying at one side of the axis of rotation, weighted matter such as fine shot, sand or other material which will gradually be released and fall back into the underlying buckets as the drums are rotated, and to provide suitable means for transmitting rotary motion from both ends of the beam to the drums in such manner that the weight of the material carried in the buckets will afford a definite amount of resistance to the rotation of the beam by the warp as the latter is fed into the machine during the weaving operation.

Another object is to enable the beam to be rotated backwardly independently of the weighted drums for rewinding the warp thereon in case the machine is reversed as is sometimes necessary in repairing imperfections in the fabric or for any other purpose.

A further object is to provide means for successively transmitting motion from the end drums to the remaining drums and to enable any drum to be disconnected from its adjacent drum for varying the load or tension upon the warp.

Other objects and uses relating to specific parts of the device will be brought out in the following description.

In the drawings, Figure 1 is a rear elevation, partly in section, of a warp beam and tensioning device for the warp operatively connected thereto, the dotted lines at the inner ends of the load carriers indicating the position to which the inner end carriers may be adjusted for disconnecting them from the adjacent carriers. 60

Figure 2 is an end view of the same mechanism. 65

Figure 3 is a transverse vertical sectional view taken on line 3—3, Figure 1.

Figure 4 is an end face view of one of the rotary carriers showing more particularly the position of the clutch members thereon. 70

Figure 5 is an enlarged top plan, partly in section, of one of the drums and adjacent portion of the main supporting frame showing more particularly the clutch for connecting and disconnecting the driven sprocket 75 wheel to and from said drum.

Figure 6 is an enlarged detail sectional view taken on line 6—6, Figure 2.

Figure 7 is an end view of a modified form of my invention. 80

In order that my invention may be clearly understood I have shown a portion of the main supporting frame —1— of a silk weaving loom upon which is mounted a warp beam —2— and a shaft —3—, the warp beam being provided with suitable trunnions —4— which are journaled in bearings —5— on opposite sides of the frame to permit the rotation of the warp beam. 85

The shaft —3— is preferably stationary 90 and is secured by set screws —6— in bearings —7— also on opposite sides of the machine so that the shaft —3— extends parallel with but in a plane some distance below and at the rear of the warp beam —2— for receiving and supporting a plurality of in this instance, two rotary circular drums —8— which are arranged coaxially in longitudinally spaced relation to form an intervening passage —9— through which access may be had to the underlying mechanism of the loom, and also to balance the weight at both ends of the warp beam and, furthermore to permit certain sections of the drums to be displaced endwise from other sections as will be presently described. 95

Each drum —8— is made up of a series of in this instance, five similar and interchangeable hollow sections —10— arranged end to end coaxially and loosely upon the 100 105 110

shaft —3— for relative rotary movement, each section constituting a closed hollow carrier capable of receiving and retaining weighted matter —a— such as fine shot, sand or other heavy comminuted material which may be free to fall back on to the bottom of the carrier as it is carried upwardly by the rotation thereof.

For this latter purpose, each carrier is 10 provided with a circumferential series of vanes or flanges —11— projecting inwardly from the periphery thereof in uniform circumferentially spaced relation and preferably having their inner ends deflected in 15 the direction of rotation to constitute a corresponding number of buckets for receiving the weighted material as —a— and carrying it from the bottom upwardly some distance to the rear of the axis of rotation and allowing 20 it to fall back into the bottom of the carrier as the several buckets approach their limits of upward movement.

By this arrangement, the rotation of each 25 carrier in the direction indicated by the arrow α will elevate a predetermined load tending to resist such rotation while the aggregate load of the several carriers is utilized in the manner presently described in 30 maintaining a uniform tension upon the warp through the medium of suitable connections between the carriers and warp beam.

The carriers —10— at the extreme outer 35 ends of the drums —8— are preferably driven directly from the corresponding ends of the warp beam through the medium of two sprocket chains —12— and sprocket wheels —13— and —14—, the sprocket wheels —13— being loosely mounted upon 40 their respective trunnions —3— for relative rotary and axial movement in one direction thus permitting relative rotation of the warp beam —2— in an opposite direction.

The opposite ends of the warp beam —2— 45 and adjacent ends of the sprocket wheels —13— are provided with cooperative ratchet clutch teeth —15— yieldingly held in engagement by coil springs —16— and arranged to transmit rotary motion from the 50 warp beam to the sprocket wheels as said warp beam is gradually rotated by the feed of the warp into the machine during the weaving operation and permitting the free backward rotation of the warp beam by 55 hand relatively to the sprocket wheel —13— for rewinding the warp thereon in case the weaving mechanism should be reversed for any reason to such an extent as to slacken the warp.

60 The sprocket wheels —14— are also loosely mounted upon opposite ends of the shaft —3— but are normally in driving connection with the adjacent carriers —10— through the medium of clutch collars —17— which are slidably upon the hubs of the ad-

jacent sprocket wheels —14— and are provided with clutch pins —18— movable in guide openings in the sprocket wheel into and out of similar openings —19— in the adjacent carriers —10— thus permitting the driving means for the carriers to be connected to and released from driving connection with the sprocket wheels and warp beam.

Any suitable means may be employed for shifting the clutch collars —18— to and from their locking positions and for this purpose is shown a pair of hand levers —20— fulcrumed intermediate their ends at —21— to suitable brackets —22— on the main supporting frame —1— and provided with forked arms —23— engaging in annular grooves —24— in said collars.

As previously stated, rotary motion is transmitted from the beam —2— to the outer end carriers —10— through the medium of the chain belts —12— and that each carrier —10— is loosely mounted upon its supporting shaft —3— and it therefore becomes necessary to provide means for transmitting rotary motion from the outer end carriers to the remaining carriers in order that they may all operate in unison and at the same time be capable of detachment from the companion carriers for varying the load resistance, and resultant tension on the warp.

For this latter purpose, the adjacent end faces of the several carriers are provided with clutch members —25— consisting of radial ribs, those of each carrier normally overlapping upon those of the adjacent carrier for successively imparting rotary motion from one carrier to the other from the outer ends inwardly and also permitting the carriers to be successively detached one from the other from the inner ends toward the outer ends of the drums by simply moving said carriers axially and inwardly as shown by dotted lines in Figure 1.

In order that the driving connection between the adjacent carriers may be automatically maintained, the adjacent edges of companion ribs —25— are undercut so as to interlock with each other axially as well as circumferentially which permits the carriers to be easily displaced one from the other from the inner ends toward the outer ends of the drums by slight forward rotation followed by inward axial movement, the object of which is to permit the load upon the warp to be expeditiously varied at will by simply disconnecting one or more carriers from the remaining carriers.

Any suitable means may be employed for tightening the chain belts —12— and for this purpose is provided idler pulleys —26— rotatably mounted upon separate brackets —27— which in turn are slidably mounted upon the adjacent portions of the main supporting frame —1— and are held in their

adjusting position by clamping bolts —28—, Figure 6.

The carriers —10— may be made of sheet metal or other suitable material and are 5 provided with removable end plates —10'— normally held in place by screws —29—, Figure 1 to permit access to the interior for filling and removing the material —a— when desired.

10 Suitable brake members —30— are provided for engaging the peripheries of the end carriers —10— and as shown in Figure 2, are mounted upon pedal levers —31— adapted to engage toothed racks —32— for 15 holding the brake members in their adjusted position, the object of these brakes being to hold the carriers against backward rotation in case the warp is slackened by reversing the weaving mechanism. The construction shown in Figure 7 is somewhat similar to that previously described except that the load carrying drums as —8— and their supporting shaft as —3— are disposed mainly at the front of the vertical plane 25 of the axis of the warp beam —2— and that the chains as —12'— are arranged to carry extra but relatively smaller sprocket wheels —14'— which are mounted upon suitable levers —40— having their front ends pivotally mounted upon opposite ends of the shaft —3— and their rear ends provided with weights —41—.

The sprocket wheels —14'— are journaled upon studs —42— which are adjustable forwardly and rearwardly in slots —43— in the levers —40— and are held in their adjusted position by nuts —44—, thereby serving as belt tighteners for the chains and also as a means for placing additional load upon 40 the warp beam —2— when the latter is actuated by the warp during the weaving operation by reason of the tendency of rear sides of the chain to lift the weight.

The weight —41— is also adjustable 45 along and upon the rear end of the lever —40— to vary the load.

This device is particularly useful in the use of extra heavy warp which requires an increased tension which may be varied by 50 releasing one or more of the carriers of the drums —8— or by shifting the position of the stud —42— along the slot —43— or by varying the positions of the weights —41— along the levers.

55 *Operation.*

When the machine is running normally for weaving purposes, the warp as —w— is unwound from the beam —2— thereby rotating said beam in the direction indicated by arrow —y— which through the medium of the clutch teeth —15— imparts rotary motion to the adjacent sprocket wheels —13— and thence through the chains —12— to the sprocket wheels —14— from which

latter rotary motion is imparted to the adjacent end carriers —10— through the medium of the clutch pins —18—.

This rotary motion of the end carriers —10— is transmitted to the remaining carriers through the clutch ribs —25—.

This rotary motion of the beam and carriers is of course, very slow and regularly intermittent as the weft threads are fed through the warp by the action of the shuttles in the usual manner, and owing to the fact that the weighted material as —a— is carried upwardly some distance to the rear of the axis of rotation of the carriers and the buckets on the front side of the axis 80 are empty, it produces a definite load resistance to the rotation of the warp beam and thereby produces a definite tension upon the warp threads which load and tension is substantially constant by reason of the 85 chain belt connections between the beam and load carrying drums.

It is advisable to place upon the shaft —3— as many carriers as may be required to give the maximum load or tension upon 90 the strongest warp and then to regulate the load or tension by disengaging one or more of the inner-most carriers from their companion carriers.

This reduction of the load in the manner 95 described may be required during the weaving operation as the warp is gradually unwound from the beam and may be readily affected without stopping the machine or producing any excessive strains upon the 100 warp by simply detaching one or more of the inner carriers and allowing it to idle loosely upon the shaft —3—.

It is also evident that similar load adjustment may be made to conform to the 105 requirements for different kinds of warp according to the nature thereof.

In case it should become necessary to reverse the operation of the machine for any purpose, which would cause a slackening of 110 the warp between the harness and the beam, the latter may be readily rotated backward by hand through the slipping of the clutch connections —15— without affecting the operation of the sprocket wheels or chains in 115 which case it is advisable to set the brakes —30— to hold the tensioning drums against backward rotation, leaving the load just where it was at the time of reversal so that when the regular weaving operation of the 120 machine again begins, the brakes may be released and the warp tensioned by the load in the several carriers —10— which may then be in operation.

It will also be noted that a similar release result may be obtained by releasing the clutch pins —18— in which case the warp beam may be rotated backward without affecting the operation of the weighted carriers.

41
Although, I have shown and described two drums, each composed of a plurality of in this instance five similar sections or load carriers, it is evident that the number of drums may be varied and that the number of sections in each drum may also be varied without departing from the spirit of this invention so long as a plurality of sections or carriers are employed in such manner that one may be detached from the other for varying the warp tensioning load.

I claim:

1. In a warp-tensioning device for looms, a warp-beam, a plurality of relatively rotatable coaxial carriers each having means for maintaining a substantially uniform load resistance to its rotation in one direction, clutch connections between said carriers, and driving connections between the warp-beam

and one of said carriers to rotate the latter 20 in said direction.

2. In a warp tensioning device for looms, a warp beam, a plurality of hollow coaxial carriers relatively rotatable about a horizontal axis and each containing weighted 25 matter loose therein and means for lifting said matter at the upwardly moving side thereof and for releasing it as it approaches the top, driving connections between the beam and one of the carriers, and clutch 30 connections between the several carriers.

In witness whereof I have hereunto set my hand this 27th day of January, 1923.

JOHN NEUROTH.

Witnesses:

H. E. CHASE,
RITA CAMPOLIETO.

Certificate of Correction.

It is hereby certified that the name of the assignee in Letters Patent No. 1,529,497, granted March 10, 1925, upon the application of John Neuroth, of Syracuse, New York, for an improvement in "Warp Tensioning Devices for Looms," was erroneously written and printed as "Harry B. Knecht," whereas said name should have been written and printed as *Henry B. Knecht*, as shown by the records of assignments in this office; and that the said Letters Patent should be read with this correction therein that the same may conform to the record of the case in the Patent Office.

Signed and sealed this 31st day of March, A. D. 1925.

[SEAL.]

KARL FENNING,
Acting Commissioner of Patents.
